UNITED STATES PATENT OFFICE.

RAYMOND W. BOWNE, OF LYNN, MASSACHUSETTS, ASSIGNOR TO UNITED STATES CARTRIDGE COMPANY, OF LOWELL, MASSACHUSETTS, A CORPORATION OF MASSACHUSETTS.

MEANS FOR INDENTING RADIATOR TUBES.

Application filed January 20, 1923. Serial No. 613,884.

This invention pertains to the manufacture of thin metallic tubes such for example as are employed in the manufacture of radiators for use with internal combustion engines, and relates more particularly to means for forming indentations in the cylindrical walls of such a tube without crushing, warping, or unduly straining the material of the tube as a whole.

In order to break up the air stream flowing through such radiator tubes, it has been found expedient to provide projections upon the inner surfaces of the tubes which act as baffles producing swirls and eddies in the stream of air so that substantially every molecule of the flowing air is brought into intimate, heat exchanging contact with the tube wall. When such tubes are formed from thin metal, as for example seamless copper tubing such as may be produced by an extrusion process, the only practical mode of forming the baffles or inwardly directed projections, is to indent the tube by pressure from the outside, but as these tubes are sometimes only .006 of an inch thick, it is manifestly difficult to form the indentations without seriously distorting the tube as a whole or stressing the metal at or near the indentations to an undesirable degree.

The object of the present invention is accordingly to provide improved means capable of forming the desired indentations in such tubes accurately and expeditiously and without damage to the tube as a whole or imposing undue strain upon the metal adjacent to the indentations, and embodying provisions for minimizing wear of the indenting elements as well as for adjusting such elements to compensate for any wear which may occur. In the accompanying drawings a preferred embodiment of the invention is illustrated by way of example, and in such drawings:

Figure 1 is a fragmentary vertical cross sectional view of a machine adapted for performing the indenting operation and embodying tube clamping and indenting elements constructed in accordance with the present invention.

Fig. 2 is a front elevation of one of the clamping jaws of the machine of Fig. 1,

showing the present improvements as applied thereto.

Fig. 3 is a horizontal cross section on the line 3-3 of Fig. 2 looking in the direction 65 of the arrows annexed to such line.

Fig. 4 is a vertical cross section on the line 4-4 of Fig. 2, the view being turned 90° from the position of Fig. 2 for convenience in illustration.

Fig. 5 is a front elevation of the other of the clamping jaws showing the present invention applied thereto.

Fig. 6 is a vertical cross section on the line 6-6 of Fig. 5.

Fig. 7 is a fragmentary vertical cross section on the line 7-7 of Fig. 1 showing a tube at the completion of the operation, parts of the tube being broken away for clearness in illustration; and

Fig. 8 is a side elevation of a completed tube showing one series of the indentations formed therein.

The numeral 1 indicates the bed or table of the machine mounted upon legs such as 2, 75 and being provided with an opening or slot 3 for the discharge of the completed tubes. A bracket 4 is secured to the table 1 and serves to support the fixed clamping jaw or block 5, hereinafter more fully described. 80 At the opposite side of the slot 3 the table or bed is furnished with a support 6 above which is mounted the bracket 7 providing an inclined guideway or chute 8 for the tube blanks 9. The bracket 7 is spaced from the 85 support 6 to provide a guideway for a sliding member 10 which is reciprocated in any desired manner common to the art. A flanged portion 11 of the movable clamping jaw or block 12 is secured to the end of the 90 slide member 10 by means of screws such as 11a.

Referring to Figs. 2, 3, and 4, the fixed clamping jaw or block 5 is shown as provided with a substantially flat vertical face 95 13 preferably machined off smoothly and true. A substantially semi-cylindrical recess 14 is formed in this face extending transversely across the block 5 with its axis substantially horizontal. A series of bores 100 15 is formed in the block 5 at either side of the recess 14. These bores are preferably

perpendicular to the surface 13 and intersect the latter at the opposite edges of the recess 14. As herein shown three of such bores are arranged at one edge of the recess 5 and two at the other, the bores of the two series being staggered relatively to each other. These bores are internally screw threaded for the reception of screws such as 16, and these screws are furnished with substantially spherical heads or ends 17 constituting die members which project into the recess 14 at opposite sides thereof. In order to retain the screws 16 in properly adjusted position, plugs such as 16^a may be inserted in the recesses behind the screws if desired.

Two or more bores 18 are also formed in the block 5 intermediate the two series of bores 15. These bores 18 open into the recess 14 at points substantially midway between the edges of the latter, but where they enter such recess they are of reduced diameter. Pins 19 are arranged to slide within the reduced portions of the bores 18, and these pins are provided with enlarged heads 20 which serve to limit outward movement of the pins. Springs 21 seated in the bores 18 tend normally to project the pins 19 into the recess 14, such springs bearing at their outer ends against a plate 22 secured to the block 5 by means of screws 23 (see Fig. 4). This plate in turn is provided with threaded openings for the reception of bolts 24 by means of which it is secured to the bracket 4 as above referred to. A pair of bores 25 of small diameter is also provided in block 5, such bores opening into the face 13 of the block to one side of the recess 14, the purpose of these bores being hereinafter described.

Referring to Figs. 5 and 6 the movable clamping block or jaw 12 is shown as furnished with the finished vertical face 26 in which is formed a semi-cylindrical recess complementary to the recess 14. A pair of pins 28 project from the surface 26 of the block 12 and are so spaced as to enter the bores 25 in the block 5 as the movable block 12 is brought into operative relationship to the block 5. When the movable block is brought into engagement with the fixed block 5, the semi-cylindrical recesses 14 and 27 together constitute a cylindrical tube-receiving chamber of a diameter substantially equal to the external diameter of the tube to be indented.

The block 12 is provided with a series of bores 29 which open into the recess 27 at points substantially midway between the edges of the latter. These bores preferably extend substantially radially with respect to the axis of the recess 27 and are internally screw threaded for the reception of screws such as 30. As shown in Fig. 6 these screws are provided with end portions 31 which bear against and serve to position balls 32

constituting die members seated in the ends of the respective bores and which project into the recess 27. As shown in Fig. 5 the block 12 is provided with four of the bores 29 and with a corresponding number of balls 32. Preferably these bores are so disposed that the two inner ones of the series of balls 32 lie in the same radial planes as the spherical ends 17 of the screws 16 at the lower edge of the recess 14 of the block 5 as viewed in Fig. 2. When the block 12 is moved toward the block 5, the spherical die members 17 of the block 5 would normally engage with the face 26 of the block 12 and prevent close contact of the face 26 with the face 13. To permit actual engagement of these faces, the face 26 is provided with recesses 33 and 34 into which the die members 17 may project as the clamping jaws are brought into engagement.

In Fig. 7 die elements useful in forming hexagonal heads upon the tubes either during or after indentation thereof are shown. For this purpose the female die elements 35, 36 are disposed at opposite ends of the block 13 cooperating with the corresponding male die elements 37 having hexagonal end portions 38 which enter the ends of the tube and serve to expand such ends outwardly into heads of hexagonal form. These head forming die elements, however, form no part of the present invention.

In the operation of the device the lowermost tube blank 9^a is released from the chute 8 and is engaged by the edges of the recess 27 of the block 12. Suitable means not shown, but common to the art, may be employed for supporting the tube in this position as the clamping block 12 moves to the left and into engagement with the block 5. As the blocks come into engagement the spherical die elements 17 and 32 impress the cylindrical walls of the tube with indentations such as indicated at 40 in Fig. 8. During this indentation of the tube the main body thereof is clamped firmly within the cylindrical chamber formed by the walls of the recesses 14 and 27 so that it is impossible for the tube to bulge or warp out of its true cylindrical shape under the pressure exerted by the die elements. As these die elements are of spherical curvature they form smoothly rounded depressions in the tube which merge gradually into the main wall of the tube without producing any sharp line of demarcation such as might result in the formation of incipient cracks or lines of strain. By reason of the arched form of the tube, the pressure of a spherical die against its wall results in the production of spherically curved depressions which are elongated in an axial direction.

If it be desired to form the hexagonal heads upon the tube while the tube is clamped between the blocks 5 and 12 the dies 35, 36 and 37 may be actuated to produce such

hexagonal heads before the block 12 is retracted. After the indentations have been formed, the block 12 is retracted and the pins 19, which have been depressed during the indenting operation, spring outwardly forcing the finished tube from the recess 14. In Fig. 8 the finished tube is shown as provided with the hexagonal heads and with the indentations 40 in its cylindrical surface.

10 When die elements of the type shown in Fig. 4 are employed, it is clear that if the face 13 or the recess 14 of the clamping block become worn, the die elements may be retracted, and the face of the block planed off to secure a new surface, after which the die elements may be advanced to normal operative position. It is also clear that as the die elements themselves are worn they may be advanced by rotation of the screws 16 or 20 may be withdrawn and replaced by new ones. If the arrangement shown in Fig. 6 be employed, the die elements 32, which consist of hardened steel balls, may readily be rotated when worn by retracting the screws 25 30 slightly and turning the balls within the bores 29, whereupon the screws may be tightened to retain the balls in position. Alternatively with this latter arrangement, the balls may be left free to turn, so that they 35 will continuously present free surfaces for engagement with the tube. It is contemplated that either or both forms of die may be employed to the same machine as desired.

What I claim and desire to secure by Letters Patent of the United States is:

1. Apparatus of the class described comprising tube clamping means, and means for forming a plurality of longitudinally spaced axially elongate spherically curved indentations in the wall of the tube.

2. Apparatus of the class described comprising tube positioning means, and means for forming spherically curved axially elongate indentations in the cylindrical walls of the tube.

3. Apparatus of the class described comprising tube holding means, and means for forming a plurality of series of longitudinally spaced spherically curved axially elongate indentations in the cylindrical wall of the tube.

4. Apparatus of the class described comprising tube clamping means, and means for producing a plurality of circumferentially and symmetrically spaced series of longitudinally spaced axially elongate, spherically curved, indentations in the cylindrical wall of the tube.

5. Apparatus of the class described comprising relatively movable tube clamping jaws, one at least of said jaws having a plurality of spherically curved projections for engagement with the cylindrical surface of the tube for indenting the latter.

6. Apparatus of the class described com-

prising relatively movable tube clamping jaws, and a removable die member having a spherically curved tube indenting surface projecting from each of said jaws for engagement with the cylindrical wall of a tube 70 clamped therebetween.

7. Apparatus of the class described comprising relatively movable clamping jaws provided with complementary recesses forming a tube receiving chamber and series of 75 longitudinally spaced spherically curved elements projecting into said chamber for indenting the cylindrical wall of the tube, one of said series comprising a lesser number of projecting elements than another 80 series.

8. Apparatus of the class described comprising separable elements provided respectively with complementary recesses constituting a cylindrical tube receiving chamber, and 85 three series of axially spaced die elements projecting inwardly from the walls of said chamber for indenting the cylindrical wall of a tube positioned therein, said series being spaced substantially equally apart in a 90 circumferential direction.

9. Apparatus of the class described comprising relatively movable tube clamping jaws having complementary recesses forming a tube receiving chamber, and series of die 95 members projecting into said chamber and extending longitudinally thereof, said dies having spherically curved tube engaging surfaces the die members of one series being staggered relatively to those of an adjacent 100 series.

10. Apparatus of the class described comprising relatively movable tube clamping jaws having complementary recesses forming a cylindrical tube receiving chamber, and a 105 plurality of independently adjustable die members spaced symmetrically about the axis of said chamber, said die members having spherically curved tube engaging surfaces for indenting the circumferential wall 110 of the tube.

11. Apparatus of the class described comprising a pair of tube clamping jaws, a series of die members projecting from one jaw, and two series of die members projecting from the other jaw, the several series 115 being so disposed as to engage the tube symmetrically with respect to its axis.

12. Apparatus of the class described comprising a pair of clamping jaws each having 120 a substantially semicylindrical recess collectively constituting a tube receiving chamber, a die projecting from one of said jaws into its recess at a point disposed substantially midway between the edges of the recess, and dies projecting from the other jaw at opposite edges of its recess.

13. Apparatus of the class described comprising a pair of clamping jaws each having 125 a substantially semicylindrical recess consti- 130

tuting complemental halves of a tube receiving chamber, a series of longitudinally spaced die elements projecting from the wall of one of said recesses, said series being spaced equally from the edges of the recess, and a series of longitudinally spaced die elements projecting from each edge of the other of said recesses.

14. Apparatus of the class described comprising tube clamping elements providing a tube receiving chamber, a die element projecting inwardly from the wall of said chamber, and means for adjusting said die element to project to a greater or lesser extent from the wall of the chamber.

15. Apparatus of the class described comprising a clamping member having a tube receiving recess therein, said recess having a cylindrically curved wall, a die element normally projecting from the wall of said recess, and means permitting said die element to be withdrawn from the recess.

16. Apparatus of the class described comprising a clamping block having a tube receiving recess therein and a bore opening into said recess, a die member positioned within the bore and normally projecting into the recess, and adjustable means for retaining said die member in operative position.

17. Apparatus of the class described comprising a clamping block having a substantially semicylindrical recess in one face thereof for the reception of a tube and a plurality of axially spaced radially extending bores opening into said recess, said bores being internally screw threaded, a die member positioned within each bore and projecting into the recess, and means engaging the screw threads of the respective bores for holding the dies in operative position.

18. Apparatus of the class described comprising complementally recessed elements

providing a substantially cylindrical tube receiving chamber, series of axially spaced bores in said elements opening into said chamber, each of said bores being internally screw threaded, a die member seated in each bore and normally projecting into the chamber, and threaded means engaging the respective bores for holding the dies in operative position, dies of the several series being spaced symmetrically of the circumference of the chamber.

19. Apparatus of the class described comprising a tube clamping block having a semi-cylindrical recess therein and series of bores opening into said recess at the opposite edges thereof, and die elements having operative surfaces of spherical curvature seated in the respective bores and projecting into the marginal portions of said recess.

20. Apparatus of the class described comprising a pair of relatively movable tube clamping jaws having complemental recesses forming a tube receiving chamber, spherical die elements projecting from said jaws into the chamber, and spring actuated members associated with one of said jaws for ejecting the tube from the recess therein upon completion of the operation.

21. Apparatus of the class described comprising a pair of relatively movable clamping jaws having complemental recesses forming a cylindrical tube receiving chamber, a series of spherical die elements projecting into the chamber from the opposite edges of the recess in one of said jaws, and spring actuated pins normally projecting into said latter recess between the series of die elements for ejecting the tube from said recess after the completion of the operation.

Signed by me at Lowell, Mass., this 6th day of Jan., 1923.

RAYMOND W. BOWN^D
